HOLDER FOR TOILET PAPER ROLLS

Jacques Firdmann, Venon, France, assignor to Etablissements Allibert Monestier-de-Clermont, Isere, France

Filed Mar. 23, 1972, Ser. No. 237,610

Claims priority, application France Sept. 24, 1971

Term of patent 7 years

Int. Cl. D6—06

U.S. Cl. D6—97

FIG. 1

FIG. 2

FIG. 3

FIG. 4

FIG. 5

FIG. 1 is a perspective view of a holder for toilet paper rolls showing my new design;

FIG. 2 is a front elevational view thereof;

FIG. 3 is an elevational view thereof taken from the right side of FIG. 2;

FIG. 4 is a top plan view thereof; and

FIG. 5 is a rear elevational view thereof.

I claim:

The ornamental design for a holder for toilet paper rolls, as shown.
